The ornamental design for a magnetic connector, as shown and described.

DESCRIPTION

FIG. 1 is a bottom, side perspective view of a magnetic connector showing our new design;

FIG. 2 is top, side perspective view thereof;

FIG. 3 is a front view thereof;

FIG. 4 is a rear view thereof;

FIG. 5 is a left-side view thereof;

FIG. 6 is a right-side view thereof;

FIG. 7 is a bottom view thereof; and,

FIG. 8 is top view thereof.

The dashed broken lines illustrate portions of the magnetic connector, and the dot-dash broken lines represent an unclaimed boundary; the broken lines form no part of the claimed design.
